(No Model.)

W. THORNTON & A. FERRIS.

AUTOMATIC GATE.

No. 288,601.

Patented Nov. 13, 1883.

UNITED STATES PATENT OFFICE.

WILLIAM THORNTON AND ALFRED FERRIS, OF ELKHART, INDIANA.

AUTOMATIC GATE.

SPECIFICATION forming part of Letters Patent No. 288,601, dated November 13, 1883.

Application filed July 10, 1883. (No model.)

To all whom it may concern:

Be it known that we, WILLIAM THORNTON and ALFRED FERRIS, citizens of the United States, and residents of Elkhart, in the county of Elkhart and State of Indiana, have invented certain new and useful Improvements in Automatic Gates; and we do hereby declare that the following is a full, clear, and exact description of the invention, which will enable others skilled in the art to which it appertains to make and use the same, reference being had to the accompanying drawings, which form a part of this specification, and in which—

15 Figure 1 is a perspective view of our improved automatic gate, showing the gate closed; and Fig. 2 is a perspective view of the same in an open position.

Similar letters of reference indicate corresponding parts in all the figures.

Our invention has relation to automatic gates; and it consists in the improved construction and combination of parts of the same, as will be hereinafter more fully described and claimed.

25 In the accompanying drawings, A represents the frame of the gate, which has a suitable panel, A", the top bar of the frame of the gate having a longitudinal vertical slot, 30 A', extending from its rear end to about the center of the said bar, for the purpose herein-after described.

35 H represents the fence-post, to which a latch of any suitable construction is attached, the said latch serving to hold the gate in its closed position.

40 B B' represent two uprights or standards, between which the gate slides when opened. One of the said uprights is secured in the ground a distance on one side and to the rear of the other upright corresponding to the thickness of the gate, so that a line drawn between the axes of the posts will form an angle of forty-five degrees to the plane of the gate when it is entirely closed or opened. The tops of the uprights are connected by a cross-beam, B", having one of its ends extended out beyond the top of the post B. To the under side of the cross-beam B", between

the two uprights, is pivoted the end of a downwardly-projecting rod, C, which passes through the longitudinal slot A' in the top bar of the gate, and has its lower end pivoted to the lower bar of the gate.

50 To the outwardly-projecting end of the beam B" is hung a pulley, D, through which the operating-rope E runs. This rope is fastened at one end to the forward part of the top bar of the gate, and has secured upon its free end a weight, F.

55 When it is desired to open the gate, the latch which serves to hold the gate in its closed position is raised or opened, when the weight F will slide the gate back, and, by reason of the pivoted rod C sliding in the slot 60 A', and of the peculiar arrangement of the uprights B B', the gate will be swung around at right angles to its former position, so as to leave the entire space which it previously closed free for the passage of the vehicle, as 65 shown in Fig. 2 of the drawings.

70 From the foregoing description, taken in connection with the accompanying drawings, the construction and operation of our improved automatic gate will readily be understood without requiring further explanation.

75 It will be seen that our improved gate is simple in construction, easy to operate, and, being devoid of all complicated mechanism, is not liable to break or get out of order, while 80 by constructing it to operate in the manner described the gate will be swung entirely out of the way of the passing vehicle.

Having thus described our invention, we 85 claim and desire to secure by Letters Patent of the United States—

The combination of the gate A, having a longitudinal vertical slot, A', extending through the rear half of its upper bar, uprights B B', one of which is placed on one side 90 and to the rear of the other, as described, cross-beam B", connecting the upper ends of the uprights B B' together, rod C, passing through the longitudinal vertical slot A', and pivoted at one end to the center of the cross-beam B" and at the other to the lower bar of the gate, pulley D, secured to the outwardly-projecting end of the cross-beam B", rope E,

passing through the pulley D, and secured at one end to the forward part of the gate, and weight F, fastened to the free end of the operating-rope E, all constructed, combined, and 5 arranged as and for the purpose shown and set forth.

In testimony that we claim the foregoing as

our own we have hereunto affixed our signatures in presence of two witnesses.

WILLIAM THORNTON.
ALFRED FERRIS.

Witnesses:

SAMUEL THORNTON,
HENRY C. DODGE.
